UNITED STATES PATENT OFFICE.

FRED M. SPAYD, OF VAN WERT, OHIO.

LATHING STRIP.

Application filed August 10, 1922. Serial No. 580,927.

To all whom it may concern:

Be it known that I, FRED M. SPAYD, a citizen of the United States, residing at Van Wert, in the county of Van Wert and State of Ohio, have invented certain new and useful Improvements in Lathing Strips; and I do declare the following to be a full, clear, and exact description of the invention, such as will enable others skilled in the art to 10 which it appertains to make and use the same.

This invention relates to an improved lathing strip and one object of the invention is to provide a lathing strip in which there 15 may be provided a backing strip of cardboard or other suitable material and laths extending transversely of the backing strip, certain of the laths having their ends terminating within the confines of the backing 20 strip and serving to prevent bending of the strip and the other laths extending beyond one side of the backing strip for extending in overlapping relation to the backing strip of a second lathing strip.

25 Another object of the invention is to provide a lathing strip in which the laths which extend beyond the side edge of the backing strip will have their inner ends terminating adjacent the transverse center 30 of the backing strip, the laths being slightly shorter than the width of the backing strip so that when two of the lathing strips are put in place with the extended laths overlapping the adjacent strip, the end portions 35 of the laths of the two strips will not contact.

40 Another object of the invention is to so construct the lath strips that when the lath strips are put in place with the side edges of adjacent strips contacting, the ends of the laths will be out of contact and thus permit expansion and contraction.

45 Another object of the invention is to so construct these lathing strips that when put in place, the laths of adjacent strips which extend in overlapping relation will serve as bracing means to prevent the laths having any movement which might tend to cause cracking of the plaster or 50 stucco.

55 Another object of the invention is to so construct the laths used that when viewed in cross section, they will be provided with head forming portions and reduced neck forming portions, the neck forming portions engaging the backing strip and the

space between the laths being thus formed into pockets having enlarged inner portions and reduced inlets between the laths, thus preventing the mortar or other plastic from 60 having any movement after the laths shrink in drying.

This invention is illustrated in the accompanying drawings, wherein:

Figure 1 is a view in front elevation showing two strips of lathing strips in place.

Figure 2 is a perspective view showing a portion of a lathing strip and a fragment of a second in position for moving into operative relation to the first lathing 70 strip.

Figure 3 is a fragmentary longitudinal sectional view taken along the line 3—3 of Fig. 1.

Figure 4 is a fragmentary sectional view 75 taken along the line 4—4 of Fig. 1.

The lathing strips will be formed of a suitable width according to whether it is desired to have each strip bridge three of the joists or studdings 1 as shown in Fig. 1, 80 or may be formed wider if it is desired to have the strips bridge a greater number of these studdings. The lathing strips may be of any desired length and when not in use will be rolled. When it is in use, the 85 strip will be cut the desired length so that it will reach from the top to the bottom of the space to be plastered or stuccoed. This lathing strip is provided with a backing strip 2 which may be formed of cardboard 90 or any other suitable material. This backing strip will be coated with tar or any other suitable material as shown at 3 and the laths 4 will be put in place as shown. These laths will in the preferred form be arranged in groups which have been designated by the letters A and B. The laths of the group A extend across the backing

95 strip from one side to the other but terminate in slight spaced relation to the side edges of the backing strip so that when the lathing strips are put in place against the studding, the ends of the laths 4 will terminate in spaced relation as shown clearly in Fig. 3. Therefore, the laths may 100 expand and contract without danger of having their ends contact and cause bulging. The laths of the group B are of the same length as the laths of the group A and these laths are put in place as shown 110 in Fig. 2 with their inner ends terminating adjacent the transverse center of the back-

ing strip. These laths extend beyond the side of the backing strip so that when the strips are put in place and secured to the studding the extended end portions of the 6 laths of the group B will extend in overlapping relation to the adjoining lathing strip between the laths of the groups A and terminate in slight spaced relation to the inner ends of the laths of the group B 10 of this lathing strip. By having the laths of the adjoining strip extending in overlapping relation, the strip will be prevented from being twisted out of shape and further the adjacent strip of lathing will be prevented 15 from having longitudinal movement which might tend to cause cracking of the plaster. When the strips of lathing are put in place, the studdings 1 will of course be covered and this might make it difficult 20 to tell where to drive the securing nails through the laths. Therefore, the strips of lathing will be passed through a suitable marking machine so that each lath may have its end portions and intermediate portion 25 marked by a slight indentation. These marks will show where the nails should be driven to cause the securing nails to be driven into the studding as shown in Fig. 3. When the lathing is used for holding 30 plaster or stucco, the plastic is forced in between the laths 4 and if a backing is not used, a great deal of the plaster or stucco has a tendency to fall down behind the lathing strips. The backing prevents this 35 and thus prevents a great waste of plaster and stucco.

In order to provide a means for holding a body of plaster or stucco tightly in place after drying, or in order to prevent the body of plaster or stucco from becoming loose 40 from the laths after the laths have shrunk incidental to the drying of the plaster or stucco, the inner portions of the side edges of the laths 4 are cut away to form in- 45 wardly facing shoulders. These shoulders are arranged in parallel relation to the outer faces of the laths 4, as shown in Fig. 4, so that as the laths shrink in the direction of their width as an incident to the 50 drying of the plaster or stucco, these shoulders will hold the body of the plaster or

stucco tightly and will prevent it from becoming loose. The laths 4 are therefore applicable not only to a backing strip such as the strip 2 shown in the drawings, but 55 may also be nailed directly to any flat surface to which plaster or stucco is to be applied. When the laths are not to be secured to a backing strip, such as the strip 1 shown in the drawings, but are to be applied to a 60 flat surface, they may be applied directly to such surface, no means being necessary to space the laths from the surface in order to permit them to firmly hold the mass of 65 plaster or stucco.

There has thus been provided strips of lathing which can be very easily and quickly put in place and the securing nails for the laths readily driven into the proper portions of the laths for entering the studdings. 70

I claim:

1. A lathing strip comprising a backing strip and spaced laths carried by and all extending transversely of the backing strip, 75 certain of said laths extending beyond the backing strip at one side thereof and having their inner ends terminating intermediate the width of the backing strip, thereby leaving portions of said backing strip 80 unoccupied by laths, and the remaining laths having their ends terminating within the confines of the backing strip.

2. A lathing strip comprising a backing sheet, groups of laths all extending transversely of said backing sheet, the laths of certain of said groups extending beyond one side of said backing strip and having their inner ends terminating intermediate the width of the backing strip, thereby 85 leaving portions of said backing strip unoccupied by laths, and the laths of the other groups having their ends terminating in slight spaced relation to the side edges of the backing strip. 90

3. The structure of claim 1 having the extended laths alternated between the laths terminating within the confines of the backing strip. 95

In testimony whereof I have hereunto affixed my signature. 100

FRED M. SPAYD.
